UNITED STATES PATENT OFFICE

ARTHUR T. DAVENPORT, OF WASHINGTON, DISTRICT OF COLUMBIA

DOSING DEVICE

Application filed November 24, 1930. Serial No. 497,936.

This invention relates to new and useful improvements in dosing devices and aims to provide a simple, inexpensive and widely adaptable device for use upon the tip of a spoon bowl to facilitate the pouring of liquids such as medicine therefrom.

It is well known that in administering certain medicinal substances to persons, and especially to infants and somewhat older children, considerable difficulty is often encountered in properly administering the doses. Particularly, this is true in administering cod-liver oil and castor oil to children of tender age. They frequently succeed in spilling all or a portion of the medicine from the spoon in which it is usually offered, or manage to eject from the mouth part of the administered dose. The widely increased use of cod-liver oil as a medicine for children has emphasized the need of a dosing device particularly suited to the administration of such an oily, viscous liquid to young children. I find that my invention described herein satisfies this need in a highly efficient manner.

My invention generally consists of a soft rubber sleeve adapted to be stretched over the end of any ordinary spoon bowl and being formed integrally with a nozzle which will be readily taken into the infant's mouth and which will conduct the liquid from the spoon and sleeve well into the rear of the infant's mouth so that the entire spoonful of the medicine will be taken by the child.

In the drawings wherein like reference characters indicate corresponding parts in three views:

Figure I is a perspective view of my improved dosing device as seen from the forward or nozzle end.

Figure II is a perspective view of the dosing device as seen from the rear or sleeve end.

Figure III is a detail longitudinal section through the dosing device.

Now having particular reference to the drawings, A designates a fan-shaped sleeve of soft rubber or other soft, highly elastic, waterproof material that is adapted to be stretched over the point of any ordinary spoon bowl. The bottom wall of this sleeve is formed to the curvature of the under sur-

face of a spoon bowl at its tip. B designates a moulded rib formed on the inner surface of the top side of the sleeve and extending longitudinally the full length of the sleeve. The purpose of the rib is to prevent the possibility of sealing the liquid in the spoon when the sleeve is stretched over the point of a spoon. C designates a nozzle of predetermined length and suitable diameter formed integrally with the sleeve A and communicating therewith at its closed edge. As described, this nozzle is preferably of the same material as the sleeve such as rubber or other soft, resilient substance which by reason of its nature and shape will be readily taken by an infant, and which by reason of its softness protects the infant's mouth from injury.

When the sleeve A is attached to a spoon and nozzle is placed within an infant's mouth, by upwardly tilting the spoon the medicine or other fluid within the spoon bowl will flow into the nozzle C and consequently into the infant's mouth smoothly and without spilling. The dosing device can be easily and quickly attached to or removed from any ordinary spoon which facilitates and therefore encourages frequent cleaning and sterilizing.

I am aware that various types of medicine spoons have been designed and patented and that hard, detachable guards have been used on some of these spoons or an ordinary spoon. By their nature these attachments are limited to use on a particular spoon, or interchangeably only on spoons of very like dimensions.

Wherefore I do not make any claim to the subject matter of these inventions. What I do claim as my invention is:

1. A dosing device adapted for interchangeable attachment to any ordinary spoon for delivery of liquid therefrom, said device being composed of soft rubber or other soft, elastic waterproof material, and comprising a sleeve shaped at one end to conform with the bowl of a spoon and having at the other end a nozzle of reduced diameter to discharge the contents of the spoon and sleeve, and means on the inner upper surface of the sleeve adapted to provide an outlet passage between

the sleeve and the spoon when in assembled position.

2. A dosing device according to claim 1 having an internal longitudinal rib adapted to contact with the tip of a spoon when in 5 operative position.

In testimony whereof I affix my signature.
ARTHUR T. DAVENPORT.
